ENGINE CONTROL MEANS

Frank Blymyer, Westchester, Ill., assignor to General Motors Corporation, Detroit, Mich., a corporation of Delaware

Application May 29, 1941, Serial No. 395,848

5 Claims. (Cl. 264—3)

This invention relates to control means for an engine.

It relates especially to a combined manual and governor control means for an internal combustion engine working under varying conditions of load and speed.

The object of the invention is a combined manual and governor actuated control means, such that the governor is only operative in the low and high speed ranges, to control the engine when idling and to prevent a maximum speed from being exceeded; the engine being controlled in an intermediate speed range by the manual means alone.

A more specific object of the invention is a combined manual and hydraulic governor control means of the foregoing kind.

The above and other objects of the invention will be apparent as the description proceeds.

According to the invention, the manual control means and the fuel control member are connected to spaced points of a floating lever having a third point connected to a second floating lever, at a point removed from two spaced points thereof which are respectively positioned by two independent servo motor means controlled by the governor in its high and low speed ranges respectively. When one of the servo motor means is operative, the other is stationary in a fixed position and vice versa, the first floating lever being moved differentially by the manual control means and one or the other of the servo motor means. In the intermediate speed range both servo motor means are inoperative and stationary in fixed positions, providing a fixed fulcrum for the first floating lever which is oscillated thereby by the manual control means to move the fuel control member.

The drawings show an embodiment of the invention in which the governor is of the hydraulic relay type.

In the drawings

Figure 1 is a view of the associated parts of the control means in sectional elevation.

Figure 2 is a view on line 2—2 of Figure 1.

Figure 3 is a view on line 3—3 of Figure 1 with part broken away.

Figure 4 is a view of a detail on line 4—4 of Figure 1.

As shown most clearly in Figure 1, the housing 1 contains a hollow shaft 2 driven by the engine, and provided with a governor head 3 on which flyweights 4 are pivotally mounted.

The flyweights 4 control the position of a pilot valve 7. With increasing engine speed the fly-

weights move outwards about their pivots, lifting the pilot valve 7. The governor is loaded by springs 8 and 9 which resiliently resist outward movement of the flyweights. The pressure of the springs 8 and 9 can be varied by adjustment of the abutment 10 therefor, which is slidable in a fixed guide 11.

The pilot valve 7 is a pressure balanced valve working within the hollow shaft 2. It is provided with three spaced annular grooves 12, 13, and 14, separated by lands 16 and 17, and it controls ports 20, 21, 22, 23, and 24 through the wall of the hollow shaft 2. The said ports open into annular grooves in the exterior circumference of the revolving shaft 2, through which communication is at all times maintained with ports and ducts in the housing 1, hereinafter described.

Secured to the lower end of the shaft 2 is a gear wheel 26 of a gear wheel pump which delivers lubricating oil under pressure to a chamber 28 from a chamber 29 connected with the engine lubricating system by a pipe 30.

From the chamber 28 there are ports 32 and 33 communicating at all times with the ports 20 and 23 respectively of the hollow shaft 2, and a spring loaded pressure relief valve 35 puts the chamber 28 in communication with a return line 36 to the inlet side of the pump.

Oil flowing through the ports 32 and 20 into the annular groove 12 of the pilot valve, can pass therefrom through the port 21 and ducts (not shown) to a cylinder 40 (Figure 2) containing a servo piston 41; but at the highest engine speeds, as the pilot valve 7 is lifted, the annular groove 13 puts the port 21 and hence the cylinder 40 in communication with the drain port 22 which returns the lubricating oil to the engine lubricating system through a suitable duct (not shown).

Oil flowing through the ports 33 and 23 into the annular groove 14 of the pilot valve can pass therefrom through the port 24 and ducts (not shown) to a cylinder 44 (Figure 2) containing a servo piston 45; but in the idling speed range and above, as the pilot valve 7 is lifted, its lower end first closes the port 24 and then opens it to the hollow shaft 2 through which the lubricating oil is drained from the cylinder 44, back to the engine lubricating system.

As most clearly shown in Figures 2 and 3, a bushing 48 in the housing 1, supports a short shaft 49, to the outer end of which is secured a lever arm 50 constituting a fuel control member by which fuel control mechanism (not shown) is actuated.

Secured to the inner end of the shaft 49 is a lever arm 52, the end of which carries a link pin 53 which engages a slot in one end of a floating lever 54. The other end of the floating lever 54 may be moved by a manually actuated lever 59 secured to the outer end of a short shaft 60 in a bushing 61 in the housing 1, said shaft having at its inner end a lever arm 63 carrying a pin 64 which engages a slot 65 in the floating lever 54.

Intermediate of its ends, the floating lever 54 is pivotally supported by a pin 66 on a rod 67 which is slideable in the housing 1.

The rod 67 constitutes a connecting means between the pivot pin 66 of the floating lever 54 and a pivot pin 68 intermediate the ends of a second floating lever 69, to the opposite ends of which the servo pistons 41 and 45, are respectively connected by pivot pins 71 and 72, which engage slotted holes 74 and 75, in the lever 69.

Upward movement of the rod 67 is resiliently resisted by a coil spring 77.

Movement of the rod 67 is arranged to vary the governor spring loading by movement of the abutment 10 of the springs 8 and 9 which is effected by means of a yoke 78 fulcrumed to the fixed guide 11 by pivot pins 79, and linked to the rod 67 by the pivot pin 80. As the rod 67 is lowered to reduce the amount of fuel supplied to the engine, the governor spring loading is increased and vice versa, thus tending to stabilize the pilot valve and the movements of the servo pistons controlled thereby.

A spring latch 81 holds the rod 67 and its linkages in starting position, in which the yoke 78 and the abutment 10 which is connected thereto by coil springs 82 in tension, are lifted to relieve the governor of the load of the springs 8 and 9 and the weight of the abutment 10 and associated parts whenever the engine is not running. The latch 81 is released by the pressure of the oil in chamber 28 which flows through the ports 32 and 20, the annular space 12 of the pilot valve 1, and a port 83, and thrusts against a plunger 84 whenever the engine is running. The plunger 84 has a stem 85 extending through a slot 86 in the rod 67 and releases the latch 81 by direct thrust against the end thereof.

The pilot valve 1 is provided with an extension 87 constituting a "shut down" rod through which it can be positively lifted by a lever 88 pivotally mounted on a pin 89 in the housing, and having an arm 90 which rests on the pin 64. Downward fuel closing off movement of the manual control means 59 raises the pivot pin 64, the two lever arms 88 and 90, and the pilot valve 1, to a position in which the relief port 24 of the pilot valve is open, the servo piston 45 is at the bottom of its cylinder, and no fuel is supplied to the engine. The shape of the slot 65 in the floating lever 54 is such as to permit of the aforesaid movement of the manual control means 59 to "shut down" position at any time with lost motion between the lever 63 and the floating lever 54 when the rod 67 is in the latched position.

The drawings show the position of the parts with the engine stopped, the rod 67 latched, the manual control lever 59 raised to a position in which the pin 64 is towards the bottom of the slot 65 in lever 54, with the pilot valve lowered from its "shut down" position to the starting position shown in Figure 1; a lug 92 on the lever 52 being against a stop 93, with the lever arm 50 constituting the fuel control member in a position in which no fuel is supplied to the engine.

It will be seen, however, that any further up-

ward movement of the manual control lever 59 or of the rod 67, or both, will move the lever 52 away from its stop 93, and the lever 50 to a position permitting the supply of fuel to the engine, and hence the starting of the engine. As the engine is cranked and gains speed, the oil pressure in the chamber 28 rises, releasing the latch 81, and oil flows through the port 21 to the cylinder 40 to maintain the servo piston 41 against a stop 94 in the position shown in Figure 2. At the same time the oil flows through the port 24 to the cylinder 44, raising the servo piston 45 to a maximum extent limited by the stop 95, and thereby lifting the rod 67 and with it the floating lever 54, which is turned about the pivot pin 68 and moves the lever arm 52 upwards and the lever arm 50 downwards to increase the fuel supply.

If the engine speed rises higher than the idling speed of say 450 to 700 R. P. M., the pilot valve 1 is raised by the governor weights 4, and opens the relief port 24 so that the fluid pressure in the cylinder 44 is relieved, and the servo piston 45 descends with the rod 67, which reduces the amount of fuel supplied to the engine.

Movement of the servo piston 45 under the control of the pilot valve 1 will keep the engine running in its idling speed range despite small fluctuations in load.

When, however, the manual control lever 59 is raised to supply sufficient fuel to the engine to maintain it in an intermediate speed range, the pilot valve 1 is lifted by the governor weights 4, its lower end completely uncovers the relief port 24, the cylinder 44 is drained, and the servo piston 45 returns to the position shown in Figure 2.

Both the servo pistons 41 and 45 remain in the position illustrated in Figure 2 throughout the intermediate speed range in which the automatic governing means is thus made inoperative; the pivot pin 66 remaining stationary as a fulcrum for the floating lever 54 and the engine speed with a given load being controlled solely by the manual control lever 59.

Should the engine speed rise higher than, say 1750 to 1800 R. P. M., the pilot valve 1 is lifted by the governor weights 4 to a position in which the annular groove 13 puts the port 21, and hence the cylinder 40, in communication with the drain port 22, so that the servo piston 41 moves downward with the rod 67, which reduces the amount of fuel supplied to the engine.

Movement of the pilot valve 1 is damped by a friction damper. As shown most clearly in Figure 4, this consists of a cylindrical slug 91, backed by a spring 98 in a pocket 99 in the housing 1, and bearing against the side of the extension rod 87 of the pilot valve. The pressure of the spring 98 and hence the degree of friction damping is variable by adjustment of a screw 100.

I claim:

1. Combined manual and governor control means for an internal combustion engine including a manual control means, a fuel control member, and a governor, said manual control means and said fuel control member being respectively connected to spaced points of a floating lever of which a third point spaced from the first mentioned spaced points is connected to a second floating lever at a point removed from two spaced points thereof which are respectively positioned by means responsive to the governor in its high and low speed ranges respectively.

2. The combination according to claim 1, in which the means responsive to the governor are two independent servo motor means.

3. The combination according to claim 1 in which the connection between the floating levers is a rod with spring means resiliently urging the rod, the floating levers and the fuel control member in a direction to reduce the fuel supply.

4. The combination according to claim 1 in which the connection between the floating levers is a rod with spring means resiliently urging the rod, the floating levers and the fuel control members in a direction to reduce the fuel supply, there being means connected with the rod for in-

creasing the governor spring loading upon movement of the rod in said direction.

5. In an engine fuel control, the combination of an engine driven centrifugal governor, an engine driven source of fluid under pressure, a pair of cylinders containing pistons movable by the pressure fluid and operatively connected with a fuel control member, and pilot valve means controlled by the governor to supply pressure fluid to said cylinders, to cut off the supply thereto, and to control the efflux from one of said cylinders in the low speed range of the governor and from the other cylinder in the high speed range of the governor.
